SPRING DETENT

Armas J. Saarinen, San Francisco, Calif., assignor to Granberg Meter Corporation, San Francisco, Calif., a corporation of California

Original application April 13, 1936, Serial No. 74,183. Divided and this application November 30, 1936, Serial No. 113,499

2 Claims. (Cl. 188—81)

This application is a division of my U. S. application Serial No. 74,183, filed April 13, 1936 on improvements in Registers.

The object of the present invention is to provide an exceptionally simple and inexpensive, yet an efficient means to limit retrograde movement of a shaft, the device being intended primarily to limit such movement of the resetting shaft of a register, although not restricted to this particular field of use.

With the foregoing in view, the invention resides in the novel subject matter hereinafter described and claimed, description being accomplished by reference to the accompanying drawings.

Fig. 1 is a partial end elevation of a register equipped with the present invention and illustrating the manner in which the register resetting shaft may rotate uninterruptedly in one direction.

Fig. 2 is a view similar to Fig. 1 but illustrating the manner in which the invention acts to limit retrograde rotation of the shaft.

Figs. 3 and 4 are detail sectional views on lines 3—3 and 4—4 respectively of Figs. 1 and 2.

In the drawing above briefly described, 5 denotes the base of a register frame and 6 has reference to a vertical end member of said frame through which the register resetting shaft 7 passes. While this shaft must have free rotation in one direction, and preferably has limited retrograde rotation, provision must be made to prevent retrograde turning to any objectionable extent, for which purpose, the present invention has been devised.

The end of the shaft 7 passing through the end plate 6, is provided in the present disclosure with two diametrically opposite laterally projecting fingers 8 which may well be formed by the opposite ends of a pin secured in an opening in said shaft. These fingers 8 are cooperable with a spring arm 9 to limit retrograde rotation of the shaft 7 without interfering with free rotation of said shaft in the intended direction.

The spring arm 9 is preferably formed from a piece of flat steel stock, having one beveled end 10 and an obliquely bent longitudinal edge 11, for purposes to appear. The arm 9 lies against the outer side of the end plate 6 and the end por-

tion thereof opposite the beveled end 10, is secured to said plate by a screw or the like 12, turning of the arm about the fastener 12 as a pivot, being prevented by a suitable pin 13. The free end portion 10 of the spring arm 9 extends to one side of the shaft 7, preferably under this shaft, and said arm is so positioned that when said shaft 7 is rotated in the intended direction, the beveled edge 11 will be successively engaged by the fingers 8, allowing these fingers to outwardly spring said arm out of their path, as will be clear from Figs. 1 and 3. However, if the shaft be turned retrogradely, one or the other of the fingers 8 will abut the end 10 of said spring arm as seen in Figs. 2 and 4, limiting the retrograde movement.

The details herein disclosed are preferably followed, but variations may be made within the scope of the invention as claimed. Also, although the invention is designed primarily for use in connection with the resetting shafts of registers, attention is again invited to the fact that it is not restricted to his field of use.

I claim:—

1. A means for limiting retrograde rotation of a shaft, comprising a laterally projecting finger on the shaft, and a spring arm mounted in a plane transverse to said shaft and having a free end positioned to abut said finger if the shaft be retrogradely rotated, said spring arm having an obliquely directed longitudinal edge in the path of said finger to allow said finger to force said spring arm out of its path when the shaft is rotated in the intended direction.

2. A means for limiting retrograde rotation of a shaft which passes through a support, comprising a laterally projecting finger on the shaft, and a spring arm disposed in a plane transverse to said shaft, one end portion of said spring arm being secured against said support, the other end of said spring arm being positioned to abut said finger if the shaft be retrogradely rotated, said spring arm having an obliquely directed longitudinal edge positioned in the path of said finger to allow said finger to force said spring arm out of its path when the shaft is rotated in the intended direction.

ARMAS J. SAARINEN.
